CLAMPING DEVICE

James Prendergast and Joseph Prendergast,
Claremont, N. H., assignors to Sullivan Ma-
chinery Company, a corporation of Massachu-
sets

Application October 20, 1932, Serial No. 638,828

5 Claims. (Cl. 81—17)

Our invention relates to clamping mechanisms, and more particularly, to clamping devices for foundries.

In foundries, and particularly in steel foundries, a great deal of grinding is necessary in removing from castings surplus metal left after the cutting off of feeding heads and gates; and fins and other superfluous metal must also be removed from a large majority of the castings produced. For this purpose, stationary grinding wheels are not wholly satisfactory, even in the case of the smaller castings which can be conveniently moved to them, because heating of the castings in grinding them necessitates interruption of the grinding operation until the pieces to be ground, cool. Moreover, the stationary grinders cannot handle large castings, for these cannot be brought within their range of operation. Swing-frame grinders have therefore been used in conjunction with stationary grinding wheels, these swing-frame grinders including a motor and a grinding wheel with a transmission connecting the two, the whole being balanced and suspended from above. These swing-frame grinders, however, have not, heretofore, readily been usable with small castings; and larger castings, too small to be held stationary by their own weight, but large enough to cause the use of the swing-frame grinder instead of stationary grinding wheels, have presented a troublesome problem in holding them stationary so that the swing-frame grinders could be used with them. Two general methods have been employed in positioning such castings for grinding, including supporting the castings with blocks upon a low bench, and also the bedding of the castings in sand boxes mounted on benches; but neither of these arrangements has been entirely satisfactory, the blocking method requiring excessive time and the sand bed method not insuring the holding of the castings stationary.

Our invention, hereinafter described, makes it possible to employ a swing-frame grinder for practically all castings below that size where the mere mass of the casting itself will hold it stationary. By the use of our invention, greater solidity or rigidity in the positioning of the castings is possible. This promotes speed, in that faster cutting is possible, safety is increased, and the castings can be repositioned and resecured far more quickly than in any other prior method.

One object of the present invention is to provide an improved mechanism for holding castings in foundries. Another and broader object is to provide an improved pressure fluid operated

clamping mechanism. A further object of our invention is to provide an improved pressure fluid operated vise adapted readily to hold a wide variety of differently shaped objects. Another object of our invention is to provide an improved pressure fluid operated clamping mechanism having adaptability to a wide range of sizes in the objects to be gripped. A still further object of our invention is to provide an improved pressure fluid operated clamping mechanism particularly adapted to use with swing-frame grinders and adapted to be as free as possible from impediment in operation by deposits of the ground material upon its bed frame. Other objects and advantages of our invention will hereinafter more fully appear.

In the accompanying drawings, in which one form of our invention is shown for purposes of illustration,—

Fig. 1 is a plan view of the improved clamp 20 with parts broken away;

Fig. 2 is a vertical section on the line 2—2 of Fig. 1, with parts broken away;

Fig. 3 is an end view from the right hand end of Figs. 1 and 2, with parts broken away; 25

Fig. 4 is an enlarged view of the clamping jaws, and

Fig. 5 is an elevational view of the adjustable clamping jaw.

Referring to the drawings, it will be observed that end pedestal or bracket frame members 1 and 2 support a suitable strong, flat, horizontal bed plate member 3. Beneath the bed plate member, and extending herein from a point adjacent one end thereof, as far as may be desired toward the other end thereof, is a suitable heavy reinforcing member 4; and the bed plate 3 and reinforcing member 4 are traversed by a series of holes 5, 5, whose axes lie in a vertical plane extending approximately centrally of the bed 30 plate for a substantial distance. These openings 5, 5 are adapted to receive a cylindrical supporting projection 6 carried by an adjustable jaw member 7 and about which the jaw member is pivotable into any desired position completely 35 about the projection axis, the adjustable jaw member 7 having adjacent its opposite ends depending feet 8, 8 which support the same against tilting laterally. The jaw member 7 has portions 9, 10 forming herein a very obtuse angle 50 with each other, and provide a concavity 11 on one side and a pointed convexity 12 on the other. Both the concave and convex opposed surfaces of the jaw member 7 are preferably provided with projections or corrugations 13, so arranged 55

as to provide a plurality of projecting gripping portions adapted to cooperate with work held between the jaw member 7 and its cooperating jaw.

Cooperating with the stationary jaw is a movable jaw member 15 having a concave work engaging portion 16 provided with corrugations or other work engaging projections 17. The concave portion 16 of the jaw member 15 may advantageously be formed so as to fit with the convex side 12 of the adjustable jaw member 7. The movable jaw member 15 is provided with a pair of feet 18 arranged near its opposite ends and adapted to maintain the jaw horizontal, these feet supporting the jaw member 15 in the same horizontal plane with the jaw member 7 and, as a result of their small surfaces in contact with the bed plate 3, permitting a minimum interference with the motion of the jaw, due to possible deposits of grindings, or the like, upon the bed plate 3. The jaw member 15 is pivotally connected at 19 with a piston rod 20 which will shortly be further described. The pivotal connection 19 provides a limited motion between the jaw member and piston rod, permitting the jaw member 15 to adapt itself, through a limited lateral turning motion, to peculiarities in shape of members to be gripped. The jaw member 7 is free to move into any desired position about its pivotal mounting while the jaw member 15 has relatively limited pivotal movement.

For the purpose of reciprocating the piston rod 20, we have provided an air motor, which may be of any suitable form, and which is generally designated 21 and comprises herein a cylinder member 22 having opposite cylinder heads 23, 24, herein respectively having feet 25, 26 supporting the motor upon the bed plate and held in position by screws or bolts 27. Obviously, a single foot at either end of the motor would be adequate, if preferred. Suitable side rods 28 hold the cylinder heads in engagement with the cylinder member 22. Within the bore 29 of the cylinder member 22 a piston 30, having suitable packing 31, is reciprocable, and to the piston 30 the piston rod 20 is rigidly connected.

Air from a suitable source of supply is admitted to the opposite ends of the motor 21 through connections 33, 34 under the control of a four-way valve 35, this valve receiving air through any suitable connection, not shown, at its supply opening 36, and being adapted to vent air as may be desired through a discharge opening 37. The piping or the valve may be so constructed as to prevent excessive speed of motion of the piston 30, and accordingly of the jaw member 15, as by providing relatively large check-valve-controlled vent passages and small supply passages, or by the use of any suitable flow controlling restrictions, if that be preferred. A suitable operating handle 38 is provided for moving the four-way valve to admit air to either end of the clamping motor 21 while venting the other, as may be desired.

The mode of operation of our invention will be readily understood. A grinder operator having a casting to be ground will position the adjustable jaw 7 in such relation to the limit of travel of the power-moved jaw 15 that the piece to be ground may readily be gripped. Which-ever side of the jaw member 7 will most advantageously cooperate with the jaw member 15 in clamping the piece to be ground, will be turned toward the jaw member 15. The piece to be ground will then be positioned against the jaw

7 and air will be admitted by movement of the handle 38 to a suitable position to admit air at the desired rate through the connection 34 to the right hand end of the clamp operating cylinder 21. The four-way valve mechanism 35 will simultaneously vent the opposite or left end of the motor cylinder 22. The clamping jaw member 15 will then move over into engagement with the piece to be held and will clamp the latter firmly between the jaw members 7 and 15, the member 15 turning, if necessary, as permitted by its pin connection 19, to adapt itself to the shape of the work piece, and the jaw member 7 pivoting as is necessary to insure a rigid, multi-point clamping engagement of the 15 casting to be held. It will be understood that the casting to be ground may advantageously rest upon the bed plate between the jaws and will be held immovable by the latter, and accordingly the grinding wheel of the swing-frame 20 grinder may be pressed with all the force consistent with proper operation which the grinder operator may bring to bear. It will be understood that when some of the surfaces requiring grinding have been ground, the work piece may 25 be released merely by moving the valve operating handle 38 to cause the piston 30 to move to the right, and when the work piece has been adjusted to its new position, the jaws may be again caused to grip it.

It will be understood that the bodily adjustability of the jaw member 7, its reversibility, and the capacity for angular movement which it possesses will, in conjunction with the power-moved and slightly angularly adjustable jaw 35 member 15, permit the clamping of an almost unlimited variety of shapes, and in a wide range of sizes, with absolute safety. It will be appreciated, moreover, that with this clamping mechanism, the fixing of a casting in the position to be 40 operated upon is a matter of seconds, rather than a matter of minutes or more with the bench and block system, and that the pressures which can be applied and the speed of the grinding operation may be much increased. It will be observed, 45 moreover, that the mechanism is relatively inexpensive, and that it is adaptable to many other uses besides that of a foundry, although the foundry use is of particular importance.

While we have in this application specifically 50 described one form which the invention may assume in practice, it will be understood that this form is shown for purposes of illustration and that the invention may be modified and embodied in various other forms without departing from 55 its spirit or the scope of the appended claims.

What we claim as new and desire to secure by Letters Patent is:

1. In a vise, a jaw member having a pin adapted to support the same against displacement and 60 having relatively small depending feet at opposite ends thereof.

2. In a vise, a jaw member having a pin adapted to support the same against displacement but providing for angular movement about the axis 65 of said pin, and having relatively small depending feet at opposite ends thereof for supporting the same in different positions thereof.

3. In a vise, a bed, a jaw member movable along the bed and comprising a body portion 70 spaced from the bed along which it is adapted to be moved, an actuating connection therefor, and at least one foot for supporting and guiding said jaw in spaced relation to the bed, and a second jaw member on said bed and with which said 75

first jaw cooperates during the clamping operation.

4. In a vise, a bed, a jaw member movable along the bed and comprising a body portion spaced from the bed along which it is adapted to be moved, an actuating connection therefor, and relatively small feet at opposite sides of said connection for guiding said jaw member with its body portion in a constant angular relation to the plane of the bed, and a second jaw member on said bed and with which said first jaw cooperates during the clamping operation.

5. In a vise, a bed, a jaw member movable along the bed and comprising a body portion spaced

from the bed along which it is adapted to be moved, actuating means therefor including an actuating connection permitting pivoting in planes parallel to the bed but precluding pivoting in places at right angles to said first mentioned planes, and relatively small feet at opposite sides of said connection for guiding said jaw member with its body portion in a constant angular relation to the plane of the bed, and a second jaw member on said bed and with which said first jaw cooperates during the clamping operation.
